ATTORNEY.

UNITED STATES PATENT OFFICE.

PETER J. NOLAN, OF CHESTER, PENNSYLVANIA.

TRANSOM ATTACHMENT.

1,417,626.

Specification of Letters Patent. Patented May 30, 1922.

Application filed February 17, 1921. Serial No. 445,858.

To all whom it may concern:

Be it known that I, PETER J. NOLAN, a citizen of the United States, residing at the city of Chester, county of Delaware, and 5 State of Pennsylvania, have invented a certain new and useful Improved Transom Attachment, of which the following is a specification.

This invention generally stated relates to a 10 transom attachment and has more especial relation to a device for opening and closing a transom.

The leading objects of the present invention are to provide a compact, durable, 15 efficient, and comparatively inexpensive attachment of the character stated which may be readily operated with one hand, is quick-acting and by which a transom may be adjusted to any desired open position. Other 20 and further objects relate to the provision of general arrangements and combinations of parts for attaining the results sought by said leading objects.

The invention consists of the improvements hereinafter described and finally claimed.

The nature, characteristic features, and scope of the invention will be more fully understood from the following description 30 taken in connection with the accompanying drawings forming part thereof, and in which:

Fig. 1, is a fragmentary view in elevation illustrating an attachment embodying features of the invention as applied to a transom.

Fig. 2, is a similar view in side elevation.

Fig. 3, is a view of the attachment in front elevation, and

40 Fig. 4, is a fragmentary view of a modified form of operating means.

For the purpose of illustrating my invention, I have shown in the accompanying drawings, two forms thereof which are at 45 present preferred by me, since the same have been found in practice to give satisfactory and reliable results, although it is to be understood that the various instrumentalities of which my invention consists can be 50 variously arranged and organized and that my invention is not limited to the precise arrangement and organization of the instrumentalities as herein shown and described.

55 In the drawings numeral 10 designates a door-frame and numeral 11 a transom

hinged thereto. Fixed to the jamb of the frame 10 as by screws, is a vertically disposed plate 12 extended forwardly from which and at right angles thereto is a 60 bracket 13 the free end of which terminates in an arm 14 disposed in parallelism with said plate 12. Journalled in said arm and plate so as to parallel bracket 13 is a relatively coarse screw 15. Numeral 16 designates a follower internally threaded for co-operation with said screw, the lower end of said follower being grooved as at 17 for tracking upon guide rail 18 of the bracket. The upper end of the follower is bifurcated 65 as at 19. Having pivotal relation with the bifurcated portion of follower 16 and the bifurcated portion of a member 20 which is fixed, as by screws, to the frame of the transom, is a link 21. Thus as the follower 16 moves along the screw 15 the transom, through said connection, is opened or closed. Fixed to screw 15 is a sprocket-wheel 22. Cooperatively engaging the sprocket-wheel 70 is a chain 23. By pulling downward upon 75 one end of the chain the sprocket-wheel may be caused to rotate the screw in the proper direction for causing the follower, through link 21, to open or close the transom. In this connection it may be stated that since 80 the nut of the follower and the screw are relatively interlocked the transom will remain in whatever position the same may be shifted to. Thus proper adjustments may be secured. Partially surrounding the sprocket-wheel 85 is a rim or flange 24 the free ends of which are inwardly directed in a curved manner as shown at 25 in Fig. 3.

Such rim or flange not only functions to retain the bight of the chain in proper position with respect to the sprocket-wheel but 90 serves to bring the runs of the chain closely adjacent to the bracket 13, see Fig. 1. Upon opposite sides of the bracket 13, adjacent to the lower ends of flange 24 are lugs 26. The 95 runs of the chain pass between such lugs and the curved ends of the flange. Instead of a chain an apertured, vertically movable rod 29, see Fig. 4, may be employed in which case the flange 24 is dispensed with.

In order to afford the follower free movement back and forth along the bracket rail said follower may if desired be provided with a roller 28.

In order to render the device reversible 110 as to right and left hand positions upon a door jamb the follower may be provided

with a double set of bifurcated portions to receive link 21, see Fig. 3.

While the above description has been restricted to a hinged transom obviously other elements pivotally mounted may be operated by the above described attachment.

What I claim is:

1. In combination a pivotal element, a fixed plate having extended horizontally therefrom a bracket the free end of which terminates in an upwardly extended arm paralleling said plate said bracket being provided with a guide-rail disposed in parallelism therewith, a screw journaled between said arm and plate in a plane above said guide-rail, a toothed wheel fixed to said screw, vertically movable means cooperatively engaging said wheel for operating said screw, a follower cooperative with said screw said follower being provided with a depending guide arm the lower end of which is bifurcated for engaging said guide-rail, an anti-friction roller journaled in the bifurcated portion of said guide arm for travel over said guide-rail and a link pivoted to the follower top and pivotally connected to said pivoted element, the axis of the pivotal connection of said link with

said follower being in the same vertical plane with the axis of said anti-friction roller whereby the stress of the operating parts and the weight of the transom is carried by said anti-friction roller thus relieving the screw from stress and weight and rendering the operation of the device more facile.

2. In combination a pivotal element, a fixed plate terminating in a bracket, a screw journaled between the free end of said bracket and said plate and in a plane above said bracket, a follower for said screw, means connecting said follower and pivotal element, a toothed wheel fixed to said screw immediately adjacent said plate, a rim carried by said plate and partially surrounding said wheel in concentric relation the lower ends of said rim being extended toward said bracket upon a curved line, oppositely disposed means carried by said bracket adjacent the lower ends of said rim and a chain cooperative with said wheel the runs of which pass between said means and the lower ends of said rim.

In testimony whereof, I have hereunto signed my name.

PETER J. NOLAN.
